(57) **CLAIM**

The ornamental design for a handle for industrial brushes, as shown and described.

DESCRIPTION

FIG. 1 is a first side view of handle for industrial brushes;

FIG. 2 is a second side view thereof;

FIG. 3 is a front view thereof;

FIG. 4 is a rear view thereof;

FIG. 5 is a top side view thereof;

FIG. 6 is a bottom side view thereof;

FIG. 7 is a first perspective view thereof;

FIG. 8 is a second perspective view thereof;

FIG. 9 is a third perspective view thereof; and,

FIG. 10 is a fourth perspective view thereof.

Any broken lines in the figures illustrate portions of the handle that form no part of the claimed design.
